UNITED STATES PATENT OFFICE.

GEORGE N. STEERE, OF WICKFORD, RHODE ISLAND.

DESIGN FOR TAPE.

SPECIFICATION forming part of Design No. 21,903, dated October 18, 1892.

Application filed August 13, 1892. Serial No. 443,040. Term of patent 7 years.

To all whom it may concern:

Be it known that I, GEORGE N. STEERE, a citizen of the United States, residing at Wickford, and doing business at Hamilton, in the 5 county of Washington and State of Rhode Island, have invented and produced a new and original Design for Tape, of which the following is a specification, reference being had to the accompanying drawing, showing 10 a part thereof.

The leading feature of my design consists in a series of parallel zigzag ribs extending transversely of the main or central portion of the tape and made up of contrasting colors, 15 and zigzag borders, also of contrasting colors, extending in oblique lines.

A is a zigzag rib formed of one color, while B represents the adjacent zigzag rib, formed of a different color. The borders C are made of a series of oblique lines D E, the former 20 being of one color, while the latter is composed of another or contrasting color.

What I claim as new, and desire to secure by Letters Patent, is—

The design for tape, substantially as herein 25 shown and described.

GEORGE N. STEERE.
